UNITED STATES PATENT OFFICE.

PHILIP A. DESLAURIERS, OF ST. PAUL, MINNESOTA.

DESIGN FOR A SIDING-PLATE.

SPECIFICATION forming part of Design No. 21,825, dated August 30, 1892.

Application filed May 5, 1892. Serial No. 431,968. Term of patent 14 years.

To all whom it may concern:

Be it known that I, PHILIP A. DESLAURIERS, a citizen of the United States, residing at St. Paul, Ramsey county, Minnesota, have invented and produced a new and original Design for a Siding-Plate for a Sheet-Metal Building-Front, of which the following is a specification, reference being had to the accompanying drawing, illustrating the same.

10 The drawing shows a plan view of the plate, fully illustrating my design. The plate is of rectangular form, having plain or unornamented edges 2. The face of the plate is

crossed by diagonal lines 3, the intermediate spaces 4 being raised and having their surfaces ornamented with irregular lines. 15

What I claim is.

The design for a siding-plate, as shown and described.

In testimony whereof I have hereunto set my hand this 22d day of April, 1892.

PHILIP A. DESLAURIERS.

In presence of—

T. D. MERWIN,
H. S. JOHNSON.
